UNITED STATES PATENT OFFICE

139,472

DESIGN FOR A TELEPHONE SUPPORTING SHELF

Robert H. Hose, Mountainside, N. J., assignor to
Bell Telephone Laboratories, Incorporated,
New York, N. Y., a corporation of New York

Application March 16, 1944, Serial No. 112,920

Term of patent 14 years

(Cl. D33—3)

To all whom it may concern:

Be it known that I, Robert H. Hose, a citizen of the United States, residing at Mountainside, in the county of Union and State of New Jersey, have invented a new, original, and ornamental Design for a Telephone Supporting Shelf, of which the following is a specification, reference being had to the accompanying drawings forming part thereof, in which:

Fig. 1 is a perspective view of the telephone supporting shelf showing my new design.

Fig. 2 is a top plan view; and

Fig. 3 is a right-side elevational view thereof.

I claim:

The ornamental design for a telephone supporting shelf, as shown.

ROBERT H. HOSE.
